J. PATON.
STREET CAR CONSTRUCTION.
APPLICATION FILED JULY 11, 1904.

UNITED STATES PATENT OFFICE.

JAMES PATON, OF ST. LOUIS, MISSOURI, ASSIGNOR TO ST. LOUIS CAR COMPANY, OF ST. LOUIS, MISSOURI, A CORPORATION.

STREET-CAR CONSTRUCTION.

SPECIFICATION forming part of Letters Patent No. 783,757, dated February 28, 1905.

Application filed July 11, 1904. Serial No. 215,986.

To all whom it may concern:

Be it known that I, JAMES PATON, a citizen of the United States, residing in the city of St. Louis, in the State of Missouri, have invented certain new and useful Improvements in Street-Car Constructions, of which the following is a full, clear, and exact description, reference being had to the accompanying drawings, forming part of this specification.

My invention relates generally to street-car vestibules, and more particularly to a removable or hinged panel in the inner wall of the vestibule, by the use of which access may be readily had to the headlight that is located in the outer vestibule-wall. Heretofore the electric headlights of street-cars and like conveyances have been located in the lower portion of the front wall of the vestibule, and when found necessary to get at the rear portion of said headlight for the purpose of repairing the same or placing a new lamp therein it has been necessary to remove the headlight from its fixed position. This involves time and labor, and it is my intention to arrange the inner wall of the car-vestibule so that access may be readily had to the headlight.

Figure I is an elevation looking against the lower portion of the inner wall of a street-car vestibule constructed in accordance with my invention. Fig. II is a vertical section taken on line II II, Fig. I. Fig. III is a view similar to Fig. I and illustrating a modified form of the opening and door in the inner vestibule-wall. Fig. IV is a vertical section taken on line IV IV, Fig. III. Fig. V is an elevation similar to Figs. I and III and showing another modification of the opening and door therefor in the inner vestibule-wall. Fig. VI is a horizontal section taken on line VI VI, Fig. V.

Referring by numerals to the accompanying drawings, 1 indicates the inner wall of a car-vestibule, the same being ornamented with the usual panels 2, and immediately in front of said inner wall is the outer wall or panel 3, which is usually a heavy sheet-metal plate and which extends from the car-platform 4 to

the vestibule-rail 5, and immediately above and resting upon said rail 5 is the vestibule-window 6. Located in the lower portion of the outer wall 3 of the vestibule is an ordinary headlight 7. Formed in the inner vestibule-wall 1, immediately back of the headlight 7, is an opening 8, preferably rectangular and into which fits a removable panel 9, which is provided on its lower edge with depending fingers 10, that normally enter pockets 11, formed in the inner vestibule-wall immediately below the opening 8 therein.

Secured to the outer face of the upper portion of the removable section of the panel 9 are suitable spring-catches 12, that engage in keepers 13, secured to the outer face of the inner vestibule-wall 1 when the panel or removable section is in its proper position.

In the modification shown in Figs. III and IV the opening 8 is closed by a door 14, that swings upon hinges 15 and which is normally held closed by a suitable catch 16.

In the modification shown in Figs. V and VI the door or panel 17 is positioned upon the outer face of the inner vestibule-wall 1 and held to slide vertically by having its side edges confined beneath overlying strips or guide-pieces 18, which are secured to the face of the inner vestibule-wall. When this door-panel 17 is in a closed position, it rests upon an inverted-L-shaped stop 18', that is secured to the face of the inner vestibule-wall immediately beneath the opening 8 therein.

With my improvement it is only necessary to remove the panel or open the door in the inner vestibule-wall and access may be thus readily had to the headlight located in the outer wall, this construction being simple, inexpensive, and in no wise unsightly.

I claim as my invention—

1. In a street-car vestibule, an inner and outer wall in which inner wall is formed an opening opposite the headlight in the outer wall, a panel closing said opening, and means whereby said panel is held in said opening, substantially as set forth.

2. In a street-car vestibule, an outer wall which carries the car-headlight, an inner wall in which is formed an opening opposite the headlight, and a door normally closing said opening, substantially as set forth.

3. In a car-vestibule, the combination of an outer wall which carries the car-headlight, an

inner wall adjacent to said outer wall, and a removable panel in said inner wall opposite said headlight, substantially as set forth.

JAMES PATON.

In presence of—

H. F. VOGEL,
M. H. MURPHY.
